UNITED STATES PATENT OFFICE.

ANTHONY P. LA ROSE, OF FESTUS, MISSOURI.

CLOTHESLINE PULLEY.

Application filed October 15, 1924. Serial No. 743,750.

To all whom it may concern:

Be it known that ANTHONY P. LA ROSE, a citizen of the United States, residing at Festus, in the county of Jefferson and State 5 of Missouri, has invented certain new and useful Improvements in Clothesline Pulleys, of which the following is a specification.

This invention relates to an improvement in clothes line or other pulleys and has particular reference to means for providing a 10 brake to hold the pulley against rotation when the line is drawn taut.

An object of the invention is the provision of a pulley having a brake associated therewith which will readily grip and hold the line against movement, and which will readily release the line upon a slight pull of the brake releasing means.

It is a further object of the invention to 20 provide a pulley of the above mentioned character which will permit of the tightening and releasing of the line without the usual knotting and twisting of the rope.

A further object of the invention is the 25 provision of a pulley of the above mentioned character constructed of few and simple parts, strong, durable, highly convenient in use and cheap to manufacture.

Other important objects and advantages 30 of the invention will be apparent during the course of the following description.

In the accompanying drawings forming a part of the application, and in which like numerals are employed to designate like 35 parts throughout,

Figure 1 is a side elevation of a complete clothes line support, showing the invention in use,

Figure 2 is an enlarged side elevation of a 40 pulley constructed in accordance with the invention,

Figure 3 is a similar view, but of the opposite side of the pulley, and,

Figure 4 is a plan view of the pulley.

45 Referring specifically to the drawings, the numeral 10 designates a housing for supporting a winding reel, such reel being shown in dotted lines as at 11. The reel may be provided with any suitable rewinding means, such as a weight 12, operating a cable 13 about a small pulley 14, which is fixed upon the shaft of the reel, and turns therewith. It is therefore obvious that upon 50 release of the clothes line, 15, the weight 55 will cause the reel to wind such line thereon.

The reel 11 and its associated elements are merely shown to illustrate a single use of the pulley, and form no part of the invention to be hereinafter described and claimed.

The numeral 16 designates a pulley having a short shaft 17. This pulley is grooved as at 18 for engagement with the clothes line 15. The numerals 19 and 20 designate side bars, provided with openings 21 and 22 for engagement with the shaft 17. The 60 bars 19 and 20 are further provided with opening 23 and notch 24, for engagement over a pivot pin 25. As clearly shown, the bars 19 and 20 are positioned upon opposite sides of the pulley 16. The bar 20 is provided with an extension arm 26 provided with an opening 27 at its outer end to be engaged with a link 28 of a chain or other flexible element 29. The chain 29 carries a 65 ring 30 to be engaged by the finger of the operator when it is desired to release the 70 brake means, to be described.

Pivotedly mounted between the arms 19 and 20 and upon the pivot 25, is a brake lever 31. 75 This lever is shaped at its lower end to conform to the curvature of the pulley 16 and is further grooved as at 33 for engagement with the clothes line when it is passed about the pulley. The opposite end of the lever 31 is formed into a hook 34 for engagement with any suitable support, such as an eyelet 35, whereby the pulley will be held against displacement. The purpose in providing the arm 20 with a notch 24, is to permit of its 80 being swung to a dotted line position where- 85 by the operator will be enabled to remove or place the clothes line upon the pulley, without the necessity of pulling the entire line therethrough.

The operation of the device is as fol- 90 lows:—

The line 15 is drawn from the reel 11 and 95 passed over the pulley and under the brake lever 31. The line is then drawn as tight as desirable, and will be held in this position 100 by the brake lever 31 due to the fact that any tendency of the line to move the pulley clockwise, causes the brake to frictionally engage the line, and force it tight against the pulley. It will be readily seen that the 105 line will pass freely over the pulley in the direction of the arrow, but will be positively held against movement in the other direction, unless released by the releasing means.

When it is desired to release the line, the 110

operator pulls down upon the chain 29, which in turn pulls the arm 20 down causing the pivot 25 to move the brake lever away from the pulley 16.

5 It is to be understood that the form of the invention herewith shown and described is to be taken as the preferred one, but that various changes in the shape, size and arrangement of parts may be resorted to 10 without departing from the spirit of the invention or the scope of the subjoined claims.

Having described my invention, what I claim as new and desire to secure by Letters Patent is:—

15 1. In a device of the character described the combination with a pulley, of a mounting therefor, a brake bar engaged with the mounting, a supporting element carried by the brake bar, a brake shoe carried by the 20 brake bar for engaging a line passed about the pulley, and means carried by the mounting for disengaging the brake shoe from the line.

25 2. In a device of the character described the combination with a pulley, of a mounting therefor, a brake bar pivotally carried by said mounting, a brake shoe carried by the brake bar and adapted to engage a line passed over the pulley, means formed 30 upon the brake bar for engagement with a support, and means carried by the mounting for moving the brake shoe out of engagement with the line.

35 3. In a device of the character described the combination with a grooved pulley, of a pair of supporting side bars therefor, of a brake bar pivotally mounted between the supporting bars and having a brake shoe adapted to engage a line passed over the 40 pulley, and means carried by one of said

supporting bars for causing said brake shoe to disengage the line.

4. In a device of the character described the combination with a grooved pulley, a pair of side supporting bars for said pulley, 45 a brake lever, means for pivotally mounting said brake lever between said bars, a brake shoe carried by said brake lever and adapted to engage a line passed over the pulley, a hooked end formed upon said brake lever and adapted to engage a suitable support, whereby said brake lever, supporting bars and pulley are supported through the medium of the brake lever, and means carried by one of said supporting bars for 50 manually releasing said brake shoe.

5. In a device of the character described the combination with a grooved pulley, of a pair of supporting bars located upon opposite sides thereof, said bars extending beyond said pulley, a brake bar pivotally mounted between said supporting bars, a brake shoe carried by said brake bar for engagement with a line passed over the pulley, a hook formed upon the brake bar for engagement with a suitable support, whereby said brake bar, supporting bars and pulley are supported through the medium of the brake bar, such supporting means causing the brake shoe to engage the said line, an arm formed upon one of said supporting bars, a flexible element depending from said arm and adapted to be engaged by the operator, whereby said arm may be pulled down to cause the brake shoe to disengage the line, and means to permit of said last named arm being swung about its pivot independently of the other supporting bar.

In testimony whereof I affix my signature.

ANTHONY P. LA ROSE.
